CLAIM

The ornamental design for a welded-on teeth for a front-end, soil-leveling attachment removably attached to a skid steer, as shown and described.

DESCRIPTION

FIG. 1 is a perspective view of welded-on teeth for a front-end, soil-leveling attachment removably attached to a skid steer showing my new design;

FIG. 2 is an enlarged scale perspective view of the soil-leveling attachment in FIG. 1 with welded-on teeth for the front end thereof and in accordance with the invention;

FIG. 3 is an enlarged scale perspective view of the welded-on teeth and the front end in FIG. 2 and in accordance with the invention;

FIG. 4 is a top plan view thereof;

FIG. 5 is a front elevation view of FIG. 3, the rear being a mirror opposite;

FIG. 6 is a right side elevational view thereof, the left being a mirror opposite;

FIG. 7 is a bottom plan view thereof;

FIG. 8 is an enlarged scale top perspective view of FIG. 3; FIG. 9 is a bottom perspective view of FIG. 8;

FIG. 10 is a front elevation view of FIG. 8, the rear being a mirror opposite; and,

FIG. 11 is a right side elevational view of FIG. 8, the left being a mirror opposite.

The broken line showing of a skid steer loader, soil leveler, and extra teeth is included for the purpose of illustrating environmental subject matter only and forms no part of the claimed design. The long dash, short dash, broken line showing in FIGS. 1-5 and 7-10 represents areas of indeterminate length and forms no part of the claimed design.

1 Claim, 10 Drawing Sheets
